OVENS

Stanley V. Joeckel, Pompton Lakes, N.J., assignor to Infra-Red Systems, a corporation of New Jersey

Filed Sept. 17, 1958, Ser. No. 761,646

2 Claims. (Cl. 219—34)

My invention relates to ovens and more particularly to ovens for industrial uses.

One of the objects of my invention is to provide an oven constructed of a plurality of components which may be assembled in a manner to provide an oven of a pre-selected size and shape to accord with a predetermined use or operation.

Another object of my invention is to provide an oven of the foregoing described character wherein various components constitute heating units capable of being arranged in a manner to effect maximum heating of a pre-selected zone.

A further object of my invention is to provide a heating unit for association with similar units to form efficient means for heat treating objects or articles confined within a restricted zone.

An important object of my invention is to provide a heating unit of the foregoing described character which is simple in construction, durable in use, efficient in operation, economical in manufacture, and lends itself to ready replacement and substitution without modification of associated units.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a vertical sectional perspective view of an oven constructed in accordance with my invention;

Figure 2 is a fragmentary sectional view of a pair of connected units and illustrating the manner in which the duct is connected thereto;

Figure 3 is an elevation of one of the heating units illustrating the heat emanating panel and grid;

Figure 4 is a sectional view taken on the line 4—4 of Figure 3;

Figure 5 is a fragmentary longitudinal sectional view of one of the units;

Figure 6 is a perspective view of one of the units;

Figure 7 is a fragmentary side elevation of one of the units illustrating the expansion slots; and

Figure 8 is a detail sectional view illustrating the manner of securing the grid to the housing.

In one form of my oven, as illustrated in the drawings, I provide a construction which is fabricated in a manner to permit a conveyor to travel therethrough whereby objects carried by the conveyor may be heat treated by the heating units 5 constituting components of the oven. It will be noted that the units 5 are connected together and arranged to provide a pair of side walls 6 and a top wall 7, plates 8 being secured, by means of bolts 9, to plates 10 disposed within the units against the inner faces of the side walls to anchor the units 5 thereof together in fixed relation. In the present form of the invention, the

2

top wall 7 comprises a plurality of central units 5 arranged in end to end relation and angularly related side units connected to the central units and those of the side walls 6 by means of V-shaped members or angle irons 11 having outer flanges secured to the units in substantially the same manner as the plates 8.

Reinforcing and anchoring means is provided for the connected units 5 and comprises a duct 13 which transversely embraces the oven and is connected by suitable screws to the outer faces of the adjacent unit, each of the screws being threaded into the unit as shown at 14 in Figure 2. The duct 13 is provided, on the sides of the oven, with longitudinally extending branches 15 secured to the outer faces of the adjacent units with similar screws. The duct and branches are equipped with removable covers 16 whereby access may be had to electric wires 17 extending therein. The electric wires 17, within the duct, extend through conduits 18 connected thereto and then to junction boxes 19 carried by the units whereby current is supplied to the heating units 5 by being connected to the wires 17 through the junction boxes, it being understood that the wires 17 are, in turn, connected to a source of electric current of a desired voltage, etc., and controlled by a switch and/or other desirable devices.

Each of the heating units 5 comprises a metallic housing or shell having outer, side, and end walls 20, 21, and 22, respectively, and an inner wall 23. The latter wall 23 constitutes a panel of a ceramic felt type of material capable of withstanding temperatures up to at least 2300° F. and which panel 23 provides a heat radiating face. Adjacent the panel 23, the side and end walls 21 and 22 are formed along their outer margins with T-shaped slots 24 or the like to permit expansion and contraction without distortion or damage to the walls 21 and 22 of the shell. A wire heat resistant element 25 is disposed post-jacent the panel 23 and from which emanates electrically produced heat energy, the element 25 being arranged in a predetermined pattern against the inner face of the panel 23 and in a manner in which the heat generated by the element is diffused and radiated from the outer face of the panel in the form of long infra-red rays and in an even and uniform flow throughout the area of the outer face. Within the shell or housing and postjacent the element 25 there is disposed a layer 26 of high temperature mineral wool insulation capable of withstanding at least 2300° F. and behind which layer 26 is another layer 27 of mineral wool insulation capable of withstanding at least 1900° F. Rearwardly of the layer 27 is a layer 28 of an asbestos type insulation or the like capable of withstanding at least 900° F. and which, in turn, has disposed rearward thereof a layer 29 of a magnesia type insulation capable of withstanding at least 600° F. A layer 30 of aluminum foil is disposed between the layer 29 and the outer wall 20 of the shell. Interposed between the layers 27 and 28 is a reflector panel 31 constructed of aluminum for reflecting heat outwardly towards the panel 23 as clearly illustrated in Figures 4 and 5 of the drawings.

Disposed over the outer face of the panel 23 is a wire grid 33 for securing the various components of the unit in anchored relation with each other and to the housing. The grid is secured outwardly of the panel 23 by means of a plurality of wires or rods 34 extending through the housing and components thereof and which wires having ends 35 looped over the grid and opposite ends formed with hook-like portions 36 disposed in seats 37 formed in the wall 20 of the unit as clearly illustrated in Figure 8 of the drawings. By thus attaching the wires 34 to the grid and wall 20 of the housing, expansion and contraction of the unit may obtain without damage or distortion to the various components thereof.

From the foregoing, it will be apparent that by the use of the plates 8 and various shapes of angle irons 11, the units 5 may be assembled in a predetermined order to provide an oven of a desired shape for accommodating therein a particular type of work to be heat treated. Furthermore, in some instances, some units may be arranged in opposed relation with other units which are not energized with respect to heat in those instances where it is desired to confine the heat to a particular zone on one or more sides of the work. Also, it will be apparent that my novel form of oven may be constructed in a manner wherein the ends may be closed by means of suitable doors or the like to subject the work therein to a prolonged period of heat treatment or the ends may be provided with openings whereby a conveyer may continuously move the work through the oven for receiving the heat treatment thereof. I have found that my invention provides many advantages over ovens which are dependent upon heat generated by bulbs, tubes, or other form of glass heating elements, the following being a few of the advantages obtainable by the use of my invention:

a. *Flexibility*.—The heating units are completely self-contained and can be stacked in any configuration, like building blocks, to best take care of a heating requirement. Plant operations are thus freed from "rigid oven" limitations.

b. *Even heat*.—No hot or cold spots, uniform heat over entire area of radiating panel.

c. *High efficiency*.—Almost all the heat produced may be confined to a work zone.

d. *Accurate temperature control*.—Immediate heat which may be accurately adjusted with conventional controls.

e. *Quick hook-up*.—Only two wires to connect for each heating unit.

f. *Safety*.—Heating units are well insulated; housings or shells remain at safe temperature.

g. *Space economy*.—Heating units are easily disassembled and removed when heating requirements change.

h. *Minimum maintenance*.—No glass bulbs, tubes or panels to break or burn out.

i. *"Color blind" radiation*.—Each heating unit heats materials of all colors and finishes equally well.

j. *Long life*.—Virtually indestructible.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined solely to the use herein disclosed in connection therewith as it may be utilized for any purpose to which it is adaptable. It is, therefore, to be understood that the invention is not limited to the specific construction as illustrated and described, as the same is only illustrative of the principles involved which are capable of extended application in various forms, and the invention comprehends all construction within the scope of the appended claims.

Furthermore, it is pointed out that the heat radiating panel, which is constructed of a ceramic felt type of

material, effects an even distribution of the heat throughout the entire area of the panel thereby differentiating from ordinary units wherein heating units such as lights, resistance wires, etc. are arranged in clusters which function to establish hot and cold spots throughout the heat distributing area of the ordinary unit.

What I claim is:

1. In an oven construction, a plurality of spaced walls having individual heating units mounted in abutting relation with respect to each other unit and defining a chamber constituting a heating zone, coupling means connecting said walls together in a manner to form a chamber of a preselected shape for accommodating work therein and with said units being transposable to form chambers of other shapes, each of said units having flat side and end wall surfaces for abutting engagement with associated side and end wall surfaces of contiguous units, a heating element carried by each of said units for emanating infra-red rays, a panel incorporated in each unit in contiguous relationship with said element for uniformly distributing heat from the respective element, a grid over each of said panels, rods extending through each of said panels and interconnecting each of said grids and an outer wall of each of said units for maintaining components of each unit in connected relationship, and electrical wire from a source of electrical energy connected to said elements for energizing the latter whereby to heat treat work disposed in said zone.

2. An electrical heating unit comprising a housing having rear and side walls coacting to define an open front, a heat radiating panel closing said front, a wire heating element for producing heat energy disposed in said housing postjacent said panel and arranged in a manner to distribute heat substantially uniform throughout the area of said panel, insulating material disposed in said housing between said rear wall and said element, a heat reflecting member extending through said material for reflecting heat from said element outwardly through said panel, a grid disposed over said panel, rods extending through said material and said panel and connected to said housing and said grid for maintaining the latter and said panel in connected relation with said housing, electric wiring extending through said housing and connected to said element for energizing the latter, said side walls being slotted about their margins adjacent said panel to permit expansion of said housing when said element is energized.
